US0D1092320S

(12) **United States Design Patent** (10) Patent No.: **US D1,092,320 S**
(45) Date of Patent: ** Sep. 9, 2025

(54) **DRONE REMOTE CONTROLLER**

(71) Applicant: **Huanlian Wu**, Shantou (CN)

(72) Inventor: **Huanlian Wu**, Shantou (CN)

(**) Term: **15 Years**

(21) Appl. No.: **29/931,055**

(22) Filed: **Mar. 5, 2024**

(51) LOC (15) Cl. 21-01

(52) U.S. Cl.

USPC **D21/566**

(58) **Field of Classification Search**

(57) **CLAIM**

The ornamental design for a drone remote controller, as shown and described.

DESCRIPTION

FIG. 1 is a front, right and bottom perspective view of a drone remote controller showing my new design; FIG. 2 is a rear, left and top perspective view thereof; FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines depict portions of the drone remote controller and form no part of the claimed design.
